UNITED STATES PATENT OFFICE.

ALFRED BLACKMORE CLARK AND ARCHIBALD CHARLES KOESTER, OF LONDON, ENGLAND.

DESIGN FOR A COMBINED WRISTLET, NOTE PAD, AND PENCIL HOLDER.

Application filed October 29, 1927, Serial No. 23,942, and in France August 13, 1927. Term of patent 7 years.

To all whom it may concern:

Be it known that we, ALFRED BLACKMORE CLARK and ARCHIBALD CHARLES KOESTER, both subjects of His Majesty the King of England, and residents of London, England, whose post-office addresses both are 53 Conduit Street, London, W. 1., have invented a new, original, and ornamental Design for a Combined Wristlet, Note Pad, and Pencil Holder, of which the following is a specification, reference being had to the accompanying drawing, forming part thereof.

The figure is a plan view of a combined wristlet, note pad and pencil holder, showing our new design.

We claim:

The ornamental design for a combined wristlet, note pad, and pencil holder as shown.

ALFRED BLACKMORE CLARK.
ARCHIBALD CHARLES KOESTER.
